THREAD-ADVANCING REEL

Adrian J. L. Moritz, Enka, N. C., assignor to
American Enka Corporation, Enka, N. C., a corporation of Delaware

Application June 14, 1948, Serial No. 32,949

9 Claims. (Cl. 28—71.7)

1

This invention relates to thread-storage, thread-advancing devices and more particularly to a reel- or cage-like device for storing and advancing thread in a manner compatible with such after-treatments as may be required in any particular process.

In the art of after-treating wet spun rayon, the use of thread-storage, thread-advancing devices has become quite common and a large number of reel-like structures, designed for supporting and advancing thread during such treatments, have been developed.

In general, the reel- or cage-like thread-storage, thread-advancing device is characterized by a plurality of circumferentially-spaced thread-supporting rods which are arranged so that first one group of the rods supports the thread and then the other. If the groups of rods or units are arranged on converging axes, this transfer will cause thread wound on the reel or cage to progress in a generally helical path in the direction of convergence of the axes. If the two units or groups of rods are arranged on parallel axes, however, it is necessary to provide some sort of mechanism for reciprocating the thread-advancing rods and for causing them to contact the thread as they move in one direction and to recede from contact with the thread as they move in the other direction.

In general, the reel characterized by groups of rods arranged on convergent axes has met with greater success than the reciprocating-rod type due largely to the fact that reels of the latter type, as heretofore constructed, involved too many parts, were too difficult to protect from the action of any corrosive liquids that may be used incident to treating a thread supported thereon, and were not susceptible of adjustment to afford different periods of thread-storage time on the reel at a given take-up speed.

It is therefore an object of this invention to provide a thread-storage, thread-advancing device of the type involving intersecting cages mounted on parallel axes which is characterized by simplicity of design, adequate protection against corrosion and a wide degree of storage-time adjustability at any take-up speed.

It is a more specific object of this invention to simplify the construction of a two-unit thread-storage, thread-advancing device by so constructing and arranging the units that one drives the other through a mechanism which affords additionally infinite adjustment of the helix angle of the thread supported on the pair of units.

It is also contemplated according to the present

55

2

invention that the moving parts of the thread-storage, thread-advancing unit be so located and constructed that they are fully protected from the action of any treating liquid sprayed onto thread supported on and advanced along the unit.

It is another object of this invention to provide for correlated movements of a group of the component rods of a unit in a circular path in a plane normal to the long axes thereof, and in another circular path in the plane of the long axes thereof at any desired frequency while affording frequency control that is wholly independent of the take-up rate of the reel.

Other objects and advantages of this invention will be apparent upon consideration of the following detailed description of a preferred embodiment thereof in connection with the annexed drawings wherein:

Figure 1 is a view in side elevation of a thread-storage thread-advancing device constructed in accordance with the principles of the present invention, the position of thread supported and advanced thereon being shown;

Figure 2 is a view in vertical section of the thread-storage, thread-advancing device of Figure 1, the thread being removed in the interest of convenience of illustration;

Figure 3 is an end view, partially in elevation and partially in section, taken along the line 3—3 of Figure 2;

Figure 4 is a developed view of the rod reciprocating cams used in the assembly shown in Figures 1, 2 and 3;

Figures 5, 6, 7 and 8 are views in cross section taken on the line 5—5 of Figure 1 at various stages in a single cycle of rod movement; and

Figures 9, 10, 11 and 12 are views in section taken along the line 9—9 of Figure 1 at stages in the cycle of operation corresponding respectively to the stages of Figures 5, 6, 7 and 8.

Referring now in greater detail to the drawings, and more particularly to Figures 1 to 5, inclusive, thereof, the numeral 10 represents a circular plate supporting a number of rods 11 in fixed relative relation, mutually parallel, and spaced circumferentially about a zone near the periphery of the plate. The rods 11 extend to the left of plate 10 as it is shown in Figure 1, and together define an elongate cage of polygonal cross section the contour of which can be seen upon reference to Figures 3 and 5. In between the rods 11, there are mounted a plurality of rods 12, each rod 12 being supported from two points by connecting links 13 and 14. Each of the connecting links 13 is pivotally connected at one end

to the respective rod 12. For this purpose an elongate cavity 15 is provided in the inner face of each rod 12 and a wrist pin 16 is passed through the rod and link to effect the pivotal connection. The other end of each link 13 is attached to or formed with a ball-like cam follower 17 which is located in a groove 18 of a cam block 19. The cam block 19 is mounted for rotation on a shaft 20 which constitutes the main support for the entire rod assembly. Each link 13, intermediate the pivotal connection at 16 and the cam follower at 17, is pivotally attached by a pin 21 to a sleeve 22 which is mounted for rotation about the shaft 20.

A rubber boot 23 surrounds each link 13 between the pivot point at 21 and a point adjacent the wrist pin 16. The boot 23 is in the form of a flexible bellows, and closely engages the link 13 at zone 24 in a leak-proof manner. The other end of each boot 23 is provided with a collar 25 which surrounds one end of a tube 26, the other end of which is seated in an aperture in the sleeve 22. The tube 26 is provided, near its mid-point, with a radial flange 27 which is connected by bolts 28 to the body of the sleeve 22.

The purpose of the links 13 and 14 is to cause reciprocating movement of the rods 12. To this end the several links 14 are pivotally connected to the rods 12 at 29 and are also provided with cam followers designated by the numeral 30. The links 14 are each provided with boots 31 identical in structure and function to the boots 23 just described in connection with the links 13. The pivotal connection of the links 14 to the sleeve 22 is similar to the pivotal connection described in connection with the links 13.

The reciprocating movement of the rods 12 is brought about by the rotation of the sleeve 22 relative to the shaft 20. To this end, the groove 18 in the cam block 19 is so cut that, upon rotation of any cam follower 17 for 360°, that follower will be displaced in one direction for 180° of its movement and for the other 180° it will be displaced in the other direction. The nature and magnitude of this movement will be apparent upon reference to Figure 4 wherein there is shown a development of the cam groove 18. A similar groove is provided at 32 in a cam block 33 which is also mounted on the shaft 20, and the groove 32 functions in the same manner with respect to the followers 30 as the groove 18 functions with respect to the followers 17. The two cams therefore work together on the respective followers in a manner which is made clear by reference to Figure 4 wherein the successive positions of a bar 12 are indicated in broken lines. It will be understood of course that the cam blocks 19 and 33 are fixed to the shaft 20, and, to this end, set screws 34 and 35 are provided. Intermediate the cam blocks, a spacer sleeve 36 surrounds the shaft 20.

The sleeve 22 is provided with bearings at 37 and 38 so that it can rotate about the shaft 20. The bearing 37 is mounted in a hub-like structure 39 which closes the unsupported end of the sleeve 22. The other end of the sleeve 22 is attached to a plate or disc 40, the contour of which can best be understood by reference to Figure 5. The bearings 37 and 38 turn about an axis y—y of the shaft 20.

Mounted for rotation about bearings at 41 and 42, there is a sleeve 43 through which the plate 40 and the rods 11 and 12 are caused to move. The sleeve 43 is provided with a driving pulley

44 keyed thereto at 45. It is also provided with a collar at 46 having a radial flange 47 through which the collar is connected by bolts 47' to the plate 10.

5 The shaft 20 is connected to a driving pulley 48 which is keyed thereto at 49. A supporting sleeve 50, having a bearing surface 51, supports the sleeve 43; and the sleeve 43, through bearings 41 and 42, supports the shaft 20. An axial-thrust bearing 52 is provided between the pulley 48 and the sleeve 50, this bearing 52 being keyed at 53 to the sleeve 43.

10 It can now be seen that rotation of the pulley 44 will cause rotation of the plate 10, which in turn will cause movement of the bars 11 in an arcuate path concentric to the axis x—x shown in Figure 2. It is likewise apparent that the plate 10 does not directly drive the bars 12. In order that the bars may be driven from the plate 10 but yet be susceptible to a considerable measure of independent movement, a gear 54 is provided which is mounted on a stud 55 journaled in the plate 10 for free rotation. The gear 54 carries on its outer face an eccentric stud 56 which lies in a radial slot 57 in the plate or disc 40. The gear 54 meshes with a gear 58 which is keyed to the shaft 20.

15 It is now apparent therefore that, if the plate 10 moves around the shaft 20, the stud 56 acting through the slot 57 of the plate 40 will cause rotation of the sleeve 22. It is likewise apparent that the sleeve 22 is caused to move with the plate 10, regardless of what the relative speed difference between the pulleys 44 and 48 may be. 20 However, although the bodily movement of the gear 54 obviously corresponds to the bodily movement of its supporting stud 55 which is mounted in the plate 10, its individual rotation about its own axis, that is, the axis of the stud 55, depends upon the relative speed of the pulleys 44 and 48, and consequently the driving effect between the gears 54 and 58.

25 It is now apparent that the movable bars 12 actually move cyclically in three separate paths and that the construction of the present invention is such that these cycles can be adjusted with respect to frequency without bringing about any difference in the predetermined phase relationships. By operation of the cam grooves 18 and 32, the bars 12 are moved back and forth or to the left and right as viewed in Figure 2. They also move as a group in and out through the reel periphery defined by the bars 11, due to the fact that the bars 11 through their plate 10 and hub 46 rotate about the axis x—x while the bars 12 through the sleeve 22 and its bearings 37 and 38 rotate about the axis y—y. In addition to the back-and-forth movement of the bars and the relative eccentricity of the group of bars 12 to the group of bars 11, the bars of group 12 each describe for each cycle of the movements discussed above a rotary movement between the two adjacent bars 11.

30 It is felt that the nature of the movement of the bars 11 and 12 can best be understood by a concurrent reference to Figures 5 to 12, inclusive. In referring to these figures, it simplifies the understanding of the invention to regard the shaft 20 as standing still. The reason for this is that the 35 phenomenon described occurs cyclically as the plate 40 gains 360° on the shaft 20. Assuming Figure 5 to be the starting position, it is noted that after the plate 10 has carried the stud 55 90° in a clockwise direction around the shaft 20, the gear 54 and the stud 56 carried thereby will

have moved 90° in a clockwise direction around the axis of the stud 55 due to the fact that gear 54 meshes with the gear 58 and both gears are of equal diameter and operate at a 1:1 ratio. Since the plate 40 is turned by the stud 56 and not by the stud 55, it is apparent that 90° of movement of the stud 55 will bring about a movement of the plate 40 equal to 90° minus the spacing between the axes of the studs 55 and 56. Since, then, the plate 10 moves a full 90° with the stud 55 while the plate 40 is moved less than 90° at the same time, it is clear that the stationary bars 11, which move with the plate 10, will change their relative positions with respect to the movable bars which are carried by the sleeve 22 which is fixed to and rotates with the plate 40.

If reference is made to movable bar 12b in comparison with stationary bars 11a and 11b, the nature of the movement can be easily visualized. In Figure 5, movable bar 12b is half way between stationary bars 11a and 11b. In view of the lag in the movement of the plate 40 brought about by the partial rotation of the stud 56 about the axis of stud 55, bar 12b in the Figure 6 position is closer to bar 11a than it is to bar 11b.

In the next 90° of movement the stud 56 of the gear 54 moves 90° clockwise about the axis of the stud 55, and consequently causes the plate 40 to gain on the plate 10 exactly the same amount which it lagged the plate 10 in the first 90° of movement. Thus, in Figure 7, movable bar 12b, again lies exactly intermediate stationary bars 11b and 11a. During the next 90° of movement, as indicated in Figure 8, stud 56 again moves 90° about the axis of stud 55 and thus causes movable bar 12b to gain on stationary bar 11b so that the spacing at 270° is the same as the spacing at 90° , except that the movable bar 12b is close to stationary bar 11b rather than close to stationary bar 11a.

From the foregoing, it can be seen that taken individually the movable bars approach and recede from the stationary bars in a complete cycle for every 360° of gain of the plate 10 over the shaft 20. At the same time that this is occurring, the movable bars are shifting their relative radial positions with respect to the stationary bars in a manner which can best be understood by reference to Figures 9, 10, 11 and 12.

In Figures 5 and 9, the movable bar 12b which rotates about the axis y—y (see Figure 2) is projecting up through the stationary bars 11a and 11b and is in thread-supporting position. In Figures 6 and 10, after 90° of movement, the movable bar 12b is approximately the same distance from the axis x—x as the stationary bars 11a and 11b are from the axis y—y, so that the thread begins to transfer from the movable bar to the stationary bars. In the Figures 7 and 11, the stationary bars 11a and 11b are carrying the thread, and the movable bar 12b has receded within the portion of the polygon defined by the stationary bars. In Figures 8 and 12 the transfer position is again demonstrated, except that here the transfer is from the stationary bars back to the movable bar.

It can now be noted that the movable bars tend to trail the stationary bars as they give up thread to the stationary bars and tend to lead the stationary bars as they take the thread back again. This condition has been found to be productive of very smooth operation and to afford highly satisfactory transfer of the threads from one group of bars to the other during operation of the reel.

All of the foregoing description of course has no relation to the actual advancement of the thread on the reel. If reference is now made, however, to the cam grooves 18 and 32 which are fixed to the shaft 20, it will be seen that movement of the plate 40, which brings about movement of the sleeve 22, causes one cycle of reciprocation of the bars 12 for each 360° of gain of the sleeve 22 over the shaft 20. The grooves 18 and 32 are so cut that the bars are advanced toward the unsupported end of the device; that is, to the left of Figure 2 during the period while the bars 12 are carrying the thread; that is, during the period from the Figure 8 position to the Figure 6 position through the Figure 5 position. On the other hand, the bars 12 are retracted or move to the right of Figure 2 during the time that the stationary bars are carrying the thread or from the Figure 6 position to the Figure 8 position through the Figure 7 position.

All of the foregoing description has been predicated on the assumption that the shaft 20 is held stationary. When this is actually done, it is perfectly apparent that the helix angle of the thread wound on the reel will be entirely a function of the displacement caused by the cam grooves 18 and 32. However, in actual practice, the pulley 48 can be driven at some speed relative to the pulley 44. If the ratio were 1:1, a coil would be wound around the reel at the point where the thread is applied and no advancement would take place. As soon as pulley 48 is driven slower than pulley 44, thread advancement begins to occur and the helix angle can be gradually increased by decreasing the speed of pulley 48 to zero, at which time the condition illustrated will prevail. If pulley 48 is then turned in the opposite direction, it is apparent that the cycles just described can occur more than once per revolution of the plate 10 so that a larger helix angle can be produced and a more rapid rate of thread advancement will be possible.

The adjustability just described results from the correlation of the gear 54 and 58 so that one group of bars drives the other while both are maintained in synchronism with the eccentricity-producing elements of the apparatus.

By the use of the sleeve 22, the cams are fully protected from any corrosive treating liquids that may be carried on the thread to the thread-storage, thread-advancing device, and this general protective feature is maintained where the links 13 and 14 project through the sleeve 22 by the use of the boots such as are shown at 23.

By the use of the gear 58 meshing with the gear 54, it is possible to drive one group of bars from the other through a single driving pin such as 56 while insuring the individual circular movement of the movable bars, which is described in connection with and illustrated in Figures 5, 6, 7 and 8. In other words, the rotation of the shaft 20 relative to the sleeve 22 controls the frequency of transfer of the threads from the group of bars 11 to the group of bars 12. This identical movement through the cam blocks 19 and 30 controls the frequency of reciprocation of the bars 12. By the meshing of gears 58 and 54, the same relative rotation controls the frequency of the orbital movement of the bars 12. Thus, the entire device is adjustable as to frequency without requiring separate adjustment of the individual means for producing the various movements.

While this invention has been described with respect to but a single embodiment thereof, it is understood that various modifications may be

made on the basis of the description here afforded.

What is claimed is:

1. A thread-storage, thread-advancing device comprising two similar groups of bars, a shaft, means mounting the first group for movement about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, means to rotate said shaft at a different rate of speed from said first group of bars, means carried by the means mounting the first group of bars and in driving relation with said shaft for driving said second group of bars about said second axis, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

2. A thread-storage, thread-advancing device comprising two similar groups of bars, a shaft, means mounting the first group for movement about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, a pin element, a coacting element having a slot therein, one of said elements being carried by the means mounting the first group of bars and the other of said elements being carried by the means mounting the second group of bars so that a driving connection is established which is self-adjusting for the eccentricity of the two bar group mounting means, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

3. A thread-storage, thread-advancing device comprising two similar groups of bars, a shaft, means mounting the first group for movement about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, a rotatable element, means mounting said element for rotation on the means mounting the first group of bars, means for driving said element from said shaft, another element connected to the means mounting the second group of bars, one of said elements having a slot therein, a coacting pin carried by the other element, whereby a driving connection between the two bar-supporting means is established despite their relative eccentricity, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

70
75

nection between the two bar-supporting means is established despite their relative eccentricity, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

4. A thread-storage, thread-advancing device comprising two similar groups of bars, a shaft, means mounting the first group for movement about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, a first gear fixed to said shaft, second gear meshing with said first gear at a 1:1 ratio, means mounting said second gear for rotation on the means mounting the first group of bars, an eccentric pin projecting from said second gear, a plate affixed to the means mounting the second group of bars, said plate having a slot therein receiving said eccentric pin so that a driving connection is established between the means supporting the first group of bars and the means supporting the second group thereof, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

5. A thread-storage, thread-advancing device comprising two similar groups of bars, a shaft, means mounting the first group for movement about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, means to rotate said shaft at a speed different from that at which the first group of bars is rotated, a rotatable element, means mounting said element for rotation on the means mounting the first group of bars, means for driving said element from said shaft, another element connected to the means mounting the second group of bars, one of said elements having a slot therein, a coacting pin carried by the other element, whereby a driving connection between the two bar-supporting means is established despite their relative eccentricity, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

6. A thread-storage, thread-advancing device comprising two similar groups of bars, a shaft, means mounting the first group for movement

about a first axis within said shaft with the component bars in fixed spaced relation defining an elongate cage of polygonal cross section, means mounting the second group for movement about a second axis also within said shaft and lying eccentric but parallel to said first axis with the component bars lying between the bars of the first group, means for rotating said first group of bars about said shaft, means to rotate said shaft at a speed different from that at which the first group of bars is rotated, a first gear fixed to said shaft, second gear meshing with said first gear at a 1:1 ratio, means mounting said second gear for rotation on the means mounting the first group of bars, an eccentric pin projecting from said second gear, a plate affixed to the means mounting the second group of bars, said plate having a slot therein receiving said eccentric pin so that a driving connection is established between the means supporting the first group of bars and the means supporting the second group thereof, and complementary cam means carried by said shaft and the means mounting the second group of bars to cause the component bars of the second group to move longitudinally in one direction as they move outwardly of the periphery of the bars of the first group and to move longitudinally in the other direction as they move inwardly of the periphery of the bars of the first group.

7. A thread-storage, thread-advancing device comprising two groups of bars, a shaft, a plate mounted for rotation about a first axis within said shaft, a first group of said bars being attached to said plate and extending from one face thereof to define an elongate cage of polygonal cross section, a sleeve underlying said cage and surrounding a portion of said shaft, said sleeve being mounted about a second axis also within said shaft and lying eccentric but parallel to said first axis, means attached to said shaft defining a cam surface, a plurality of links each passing through said sleeve being pivotally connected thereto and coacting at one end with said cam surface and at the other end being pivotally connected to one of the bars of the second group, said links being circumferentially spaced to support the bars of the second group as a cage between the respective bars of the first group, means for rotating said plate, and means carried by said plate and in driving relation with said shaft for rotating said sleeve from said plate, the contour of said cam being such as to cause movement of the bars of the second group away from the plate during the time that the second group of bars projects beyond the periphery of the cage defined by the first group thereof and movement toward the plate as the second group of bars lies within the periphery of the cage defined by the first group thereof.

8. A thread-storage, thread-advancing device comprising two groups of bars, a shaft, a plate mounted for rotation about a first axis within said shaft, a first group of said bars being attached to said plate and extending from one face thereof to define an elongate cage of polygonal cross section, a sleeve underlying said cage and surrounding a portion of said shaft, said sleeve being mounted about a second axis also within said shaft and lying eccentric but parallel to said first axis, means attached to said shaft defining a cam surface, a plurality

of links each passing through said sleeve being pivotally connected thereto and coacting at one end with said cam surface and at the other end being pivotally connected to one of the bars of the second group, said links being circumferentially spaced to support the bars of the second group as a cage between the respective bars of the first group, resilient sealing means surrounding each link adjacent the point of pivotal connection with a bar and sealing the sleeve where the link passes therethrough, means for rotating said plate, and means carried by said plate and in driving relation with said shaft for rotating said sleeve from said plate, the contour of said cam being such as to cause movement of the bars of the second group away from the plate during the time that the second group of bars projects beyond the periphery of the cage defined by the first group thereof and movement toward the plate as the second group of bars lies within the periphery of the cage defined by the first group thereof.

9. A thread-storage, thread-advancing device comprising two groups of bars, a shaft, a plate mounted for rotation about a first axis within said shaft, a first group of said bars being attached to said plate and extending from one face thereof to define an elongate cage of polygonal cross section, a sleeve underlying said cage and surrounding a portion of said shaft, said sleeve being mounted about a second axis also within said shaft and lying eccentric but parallel to said first axis, means attached to said shaft defining a cam surface, a plurality of links each passing through said sleeve being pivotally connected thereto and coacting at one end with said cam surface and at the other end being pivotally connected to one of the bars of the second group, said links being circumferentially spaced to support the bars of the second group as a cage between the respective bars of the first group, a resilient bellows surrounding each link adjacent the point of pivotal connection to a bar and extending in sealing relation to said sleeve where the link passes therethrough whereby to render the sleeve liquid tight to protect the cam surfaces and the pivot points of the links against inleakage of liquid and outleakage of lubricant, means for rotating said plate, and means carried by said plate and in driving relation with said shaft for rotating said sleeve from said plate, the contour of said cam being such as to cause movement of the bars of the second group away from the plate during the time that the second group of bars projects beyond the periphery of the cage defined by the first group thereof and movement toward the plate as the second group of bars lies within the periphery of the cage defined by the first group thereof.

ADRIAN J. L. MORITZ.
